7 Claims. (Cl. 112—34)

The present invention relates to improvements in portable machines for stitching shoes by chain stitch.

As is known, shoe stitching machines include a horn on which the shoe is placed and within which is located a looper and a head within which is mounted a needle having an up and down movement and which cooperates with the looper, the latter performing two revolutions for each complete reciprocation of the needle.

It has already been proposed to couple together the movement of the looper mounted in the horn and that of the needle mounted in the head, without the agency of gearing or transmission members.

An object of the invention is to provide a machine in which the movement of the looper is connected to that of the needle through the medium of a connecting rod which, on the one hand, is mounted on a crank pin of a toothed wheel rotated by the looper driving device and which, on the other hand, is pivotally mounted on the sliding block mounted in the head of the machine and capable of effecting an up and down movement which enables it to actuate the needle and the associated parts.

Another feature of the invention is that the feeding point is actuated at the end of the upstroke of the needle holder by a cam carried by the sliding block and acting on the pivoting lever carrying the point, said lever being normally held in its position of rest by a spring.

According to another characteristic, the collar supporting the presser-foot is mounted on the fixed bearing and is guided in its displacement relative thereto by two positioning studs, one of which extends beyond the collar and is held in a fork which rotates in such wise that the prongs are brought into gripping relation with the stud and hold it stationary, as also the collar, during the travel of the needle holder, under the action of a cam carried by the sliding block, thus preventing the presser foot from moving relatively to the work, said fork being released on the other hand when the needle is at the end of its upstroke.

According to a further characteristic, the displacements of the needle holder on the frame of the machine are braked so as to prevent the needle holder from being displaced save when its displacement is positively controlled by the stops of the sleeve.

According to a still further characteristic, the cast-off cooperating with the needle is carried by a ring secured to the needle holder, it being, how-

ever, possible for said cast-off to slide in said ring when it has moved right down into contact with the work while the needle penetrates therein, a spring returning it to its position of rest when the needle holder rises again.

In the prior art machines, the work is held by a presser foot and released by the latter when the feed point feeds forward the work. The raising of the presser foot to release the work when the work is thus fed forward, necessitates the adjustment of the collars mounted on the needle holder, with respect to the thickness of the work to be sewn, since the collars can only fulfil their function if, at the end of the stroke, they come into contact soon enough with the collars against which they abut.

It is another object of this invention to provide a machine which overcomes this drawback by obviating the necessity for making any adjustment, whatever may be the thickness of the work.

For this purpose, according to one form of the invention, the combined feed point and presser foot does the work of the presser foot and takes the place of these two separate members. The combined feed point and presser foot is carried by a collar which slides on the needle holder and which falls by gravity and is furthermore urged by a spring to press the combined feed point and presser foot against the work, said collar being raised, to raise the combined feed point and presser foot, by a crank lever one end of which is shaped as a toothed sector which is engaged by a pawl which is displaced at the required moment by a cam carried by the sliding block operating in the head of the machine. Said pawl is carried by a support on which the said cam acts. Said collar is locked, so as to prevent the combined feed point and presser foot from being raised while the needle is being withdrawn from the work, by means of a push rod which bears firmly on the collar or a member secured thereto, and on which acts one end of a forked lever, the other arm of which is pushed by a cam.

According to a further feature of the invention, the two arms of said forked lever are of greatly different lengths so as to increase the force exerted on the push rod.

According to another feature, the presser-foot is pivotally mounted on the collar which carries it, so that it can rock and feed forward the work at the appropriate moment. The rocking of the presser-foot is controlled by the lateral displacement, dependent upon the displacement of the sliding block, of a pin which engages in a groove in the body of the presser-foot, and which

can thus rock said presser-foot without preventing the vertical displacement of the latter.

Other advantages and peculiarities of the invention will be apparent from the ensuing description taken in conjunction with the accompanying drawings in which:

Fig. 1 is a side elevation of the shoe stitching machine according to the invention.

Fig. 2 is a front elevation thereof.

Fig. 2a is an elevation of a detail of the machine.

Fig. 2b is a section on the line 2b—2b of Fig. 2a.

Fig. 2c is an enlarged detail view of a part of the machine.

Fig. 3 is a front elevation of the head of the machine, showing a modification according to the invention.

Fig. 4 is a side elevation of the same head viewed from the right side of Fig. 3.

Fig. 5 is a side elevation of the same head viewed from the left side of Fig. 3.

The machine comprises a frame 101 which may be fixed in any suitable manner on any stand, table or support. Said frame comprises a base 102 and a standard 103, which at its upper end, includes three bearings 104, 105 and 106. As in the majority of shoe-stitching machines, the base 102 carries a turn-table 107 freely rotatable about its spindle, so that the horn may be swung into various positions according to the work to be done. On the turntable is located the thread supply 109, the wax pot 110 and the thread tensioning device 111, all of which are known members in stitching machines of this type and hence need not be described in detail.

At the upper end of the horn 108 is situated the looper of standard type in machines for effecting chain stitching, and which consequently has likewise not been represented in detail. The looper 40 is rotated through a bevel pinion transmission mounted in the horn, the pinion 112 being mounted on a rod 113 constituting the spindle of the turntable 107 and which is driven from its lower end by a train of bevel pinions 114, one of 45 which is set on a spindle 115 which is rotated by a hand wheel 116 which moreover, carries a handle 117. On the spindle 115 is likewise set a spur pinion 118 which gears with a gear 119, carried by the frame of the machine. The two 50 pinions of each pair of bevel pinions 112 and 114, which transmit the movement of the wheel to the looper situated at the upper end of the horn, have the same diameter, so that the looper rotates exactly at the same speed as the wheel 55 116. On the other hand, the diameter of the gear 119, is twice that of the pinion 118, so that the former rotates at half the speed.

The gear 119 carries a crank pin on which is mounted a cranked rod 120 pivoted at its upper 60 end on a sliding block 121 moving in the head of the machine. In said sliding block screws a sleeve 122 which to this end is threaded over a portion of its length and which may be locked in its adjusting position with respect to the sliding block 121 by means of a nut 123. Said sleeve is guided at its upper end in the bearing 104 carried by the frame of the machine and likewise at its lower end in the bearing 105. Said sleeve surrounds the needle-holder rod 124, the diameter 70 of which is reduced over the portion thereof surrounded by the sleeve, but preferably it has the same diameter as the latter below the lower end of said sleeve at 125, in order to form at this point a shoulder enabling the sleeve to rest 75 against the rod. The needle-holder rod 124 it-

self passes through the bearing 106 and in the latter is located a screw 126 which, through the medium of an inner spring, presses a friction wad against the needle-holder rod 124. Said rod is thus prevented from moving freely in the bearing 106, save when it is positively displaced in the manner hereinafter to be explained.

Against the bearing 106 rests a collar 127 to which the presser foot 128 is secured and on which is pivotally mounted the lever 129 carrying at its lower end the point 130 which feeds the work forward at each stitch. On this collar are fixed by means of nuts 131, two positioning studs 132 and 133 which slide in bores of the same diameter provided to this end in the bearing 106. This provides a guide for the collar 127 when it is raised with respect to the bearing 106. Said collar is normally pressed against the bearing 106 by a spiral spring 134 which at its upper end presses against the fixed bearing 105 and at its lower end against the screw 135 screwing in a tapping of the collar 127, in order to enable the tension of the spring to be adjusted. The screw 135 is naturally recessed at its centre so as to enable the needle-holder rod 124 to pass freely therethrough.

On the frame of the machine may pivot a lever 136, the short arm 137 of which has a point of support in a portion of the collar 127 recessed at this point, whereby it is possible by pressing on the lever 136 to raise the collar with respect to the bearing 106, thus compressing the spring 134; this lifting operation naturally causes the presser foot and point to rise whereby it is possible to place the shoe to be worked on the horn 108.

The lever 129 carrying the feed point 130 is normally pushed to the left (Figure 2) at its upper end by a spring 138 in order to hold the point 130 displaced to the right. Said lever 129 carries at its upper end a roller 139 which, as the machine operates, moves over a guide-way 140 carried by the sliding block 121 and which encounters an adjustable cam 141 when said sliding block is at the top of its travel.

Again, the sliding block likewise carries a cam- 45 track 142 against which bears the end of a spring 143 so as to thrust said spring to the left during the whole duration of displacement of the sliding block, save at the end of its upstroke. Said spring constitutes the crank handle of a fork 144 horizontally trunnioned and the two prongs of which straddle the upward extension of the positioning stud 133. When the spring 143 is pushed to the left, as illustrated in the drawings, the fork 144 pivots about its axis and the two prongs fasten 50 about the stud 133, one to the right and one to the left thereof, thus locking it and preventing it from sliding. A portion 145 of the needle-holder 124 intermediate its ends is screw-threaded and on this screw-threaded portion screws a disc 146 having a lock-nut for locking the same.

Finally, on the upper screw-threaded portion of the needle-holder 124 screws a nut 147 acting as an abutment as will be indicated hereinafter and which a lock-nut holds in position.

At its lower end, the needle-holder carries a ring 148 on which is fixed a leaf spring 149, while in said ring may slide a cast-off 150, the upper end of which is bent over at right angles at 151, the leaf spring 149 normally bearing against said 70 bent end 151. The needle-holder 124 has a slot at 152, in which said cast-off is slid able, as will be explained hereinafter.

This machine operates in the following manner:—

The rotation of the toothed wheel 119, when the wheel 116 is rotated, imparts a reciprocating movement to the connecting rod 120 and hence to the sliding block 121 pivoted thereon. The sleeve 122 which is secured to said sliding block, since, as has been stated, it is screwed therein, therefore reciprocates like the sliding block. During the down stroke of the sliding block and sleeve, the latter strikes the shoulder 125 of the needle-holder 124 and from then on displaces the needle-holder. In the figures, the sliding block and sleeve have been shown in the lowered position, that is to say, the sleeve bearing against the shoulder 125 of the needle-holder. From the moment when such contact is made, the sliding block in its displacement carries with it the needle-holder and hence the needle, which penetrates into the shoe to be sewn. During the movement of the sleeve in the opposite direction, the latter immediately leaves the shoulder of the needle-holder and the needle-holder cannot be displaced even in the event of friction being produced, owing to the braking force exerted thereon by the aforesaid friction wad which the screw 126 presses against said needle-holder. When the sleeve is moved up a sufficient distance, its upper end strikes the nut 147 which is screwed on the upper threaded end of the needle-holder 124. From this moment, the sleeve rises carrying the needle-holder with it and thus extracting the needle from the shoe.

When the sleeve and with it the sliding block reach the upper end of their stroke, the cam 141 carried by the sliding block, bears against the roller 139 of the lever 129 carrying the point 130, causing the roller 139 to be displaced to the right (Figure 2) and hence the point 130 to be displaced to the left, the latter moving the shoe the distance between the stitches. At the same time, the disc 146 mounted on the needle-holder is brought against the collar 127 and raises the latter. Hence, this displacement, at the same time causes the presser foot 128 to be raised, whereby it is possible to displace the shoe which is no longer held down by said presser foot. As has been indicated above, the sleeve can screw in the sliding block whereby it is possible to regulate the moment at which the sleeve displaces the needle-holder; the depth of penetration of the needle in the work is thus adjusted according to the thickness thereof. Similarly, the nut 147 may be displaced on the needle-holder, whereby it is possible to regulate the moment at which the sliding block displaces the needle-holder on its upward path. Finally, the disc 146 likewise screws on the needle-holder, whereby it is possible also to adjust the moment at which the collar 127 is raised.

As has been explained above, the positioning stud 133 is gripped at its upper end between the prongs of the fork 144 during the whole stroke of the sliding block, both on its downward and on its return movement. Said positioning stud is secured to the collar 127 and consequently the latter is likewise locked, whereby the presser foot 128 is locked on the work and prevents the latter from jerking, as might otherwise occur.

Again, the collar 127 is held normally against the bearing 106, even when the stud 133 is not locked, by means of the spring 134 which, as has been stated, bears at its upper end against the fixed bearing 105 and at its lower end against the screw 135 screwing in the collar; thus, by screwing up or unscrewing said screw, it is possible to adjust the tension of the spring 134.

The needle co-operates with the looper to form the chain stitch in the known manner, which consequently will not be described here in detail. As is known, this operation is performed with the help of a cast-off which comes into position in front of the hook of the needle when the latter leaves the work, so as to prevent the hook of the needle from picking up the thread which it had previously dropped. When the needle-holder moves downwards to cause the needle to penetrate into the work, the cast-off 150 abuts against the work and therefore slides in the ring 148 which carries it. Due to such sliding movement, the horizontally bent portion 151 of said cast-off raises the spring 149 and moreover the vertical portion of the cast-off 150 slides in the slot 152 provided to this effect in the needle-holder. When the needle-holder rises again, the cast-off which is carried along and which then no longer rests against the work, is brought back into position by the action of the spring 149. Consequently, during the whole time that the needle rises and until its point has left the work, the counter-hook remains in front of said needle sliding along the latter.

As has been stated previously, while the sliding block 121 reciprocates under the action of the connecting rod 120, the looper revolves twice about its axis to co-operate with the needle in order to make the chain stitch.

As is seen from what precedes, the machine according to the invention is very compact, its bulk is extremely small in comparison with that of all existing machines. Furthermore, the movements of the needle-holder and the looper are coupled together in a very simple manner without any complicated transmission as is the case in existing machines. Hence, the manufacturing cost of the machine according to the invention is far lower than that of existing machines and the machine is more particularly suitable for small current repairs.

In the preceding description, it has been assumed that the machine is hand-operated which, moreover, is most convenient for light work of the type just referred to. It is evident that it could be controlled just as well by a treadle or a motor, either by means of a connecting rod driving the wheel 116, or by replacing the latter by a belt pulley.

In the machine described with reference to Figs. 1 and 2, the height of the presser foot remains constant once it is adjusted. As already explained this may, in some cases, be disadvantageous.

This drawback is avoided in the modification of the head shown in Figs. 3, 4 and 5, the presser foot and the feeding point being replaced by a single member which adjusts itself automatically for every stitch, to the height of the work on which it presses. This object is attained by means of the following mechanism:

The left side, looking at Figure 3, of the collar 121, forms a cam with which cooperates the tappet 55 constantly retracted by a spring 56 which is attached thereto and secured elsewhere to the bearing 105 fixed to the frame 103 of the machine. The tappet 55 swings about a pin 1 which passes through and is fixed in a boss 2 of the frame 103. Said tappet 55 is provided on one side with a point 59 which according to circumstances, either bears against a recessed portion of the collar 121, or against the vertical edge 57 constituting the side of the collar 121 or finally under the lower end 58 of said edge which forms a

stop. The collar 121 is also extended on this side on its under side by a member 4 which also forms a cam on its left face and, in particular, has an oblique slope 73. On the opposite side of 5 the tappet 55, the latter has a face 60 on which can bear the end of a lever 61 which is pivoted at 14 on a pin fixedly mounted on the frame of the machine. Said lever 61 carries at its other end an adjustable screw stop 63 by means of 10 which said lever 61 acts on a push stud 62. The push stud 62 presses on a rod 32 which can slide in a boss 3 secured to the bearing 106 and which is fixed to a collar 27. The stud 32 carries a knob 68 which passes in an elongated slot 69 provided 15 in a bell crank lever 5 which is pivoted on a pin 64 mounted on the frame of the machine and which carries at the end of its other arm a toothed sector 65 with which can engage a pawl 70, which is pivoted at 6 on the support 66 which 20 pivots on the same pin 64 as the bell crank lever 5, but which is independent of the latter. The pawl 70 is constantly urged towards the sector 65 by means of a spring 71 attached at 7 to the pawl support. At its other end, said pawl has a 25 heel 8 with which cooperates the stop 58 of the collar 121. The pawl support 66 is constantly urged towards the right by means of a spring 67 attached to said pawl support, for example, at the same point 7 as the spring 71 of the pawl 30 70, and attached also to the fixed bearing 105 of the machine. Said pawl support is provided with a heel 72 which constantly bears against the member 4 under the action of the said spring 67.

On the collar 27 is pivoted at 54 a lever 53 carrying at its lower end the point 50 which, as will be explained hereinafter, serves at the same time as a presser foot and feeding point. The lever 53 has an elongated opening 74 in which passes a pin 85 fixed by means of a nut 86 on a lever 76 35 which is pivoted at 71. The portion of the pin 85 which passes through the opening 74 of the lever 53 is surrounded by a roller which enables the lever 53 to swing about said pin 85. The pin 85 can be fixed at any point of the lever 76 40 which also has an elongated opening 75 which over a portion of its length registers with the opening 74 of the lever 53. In the opening 75 of the lever 76 there also passes a roller 81 fixed on a blade 78 which slides in a lug 84 of the collar 121. On the blade 78 two stops 79 and 80 are 45 fixed on either side of the lug 84, on the other hand the blade 78 passes under a spring 82 which tends to bring it into frictional engagement with a lug 83 secured to the frame through the instrumentality of the bearing 105.

This device operates in the following manner: In Figures 3, 4 and 5 the parts are shown in the position which they occupy when the collar 121 is in its lower position, the needle 9 being 50 then lowered into the work 10 and the point 50 bearing on said work. When the collar 121 begins to rise under the action of its actuating link, the tappet 55 begins to turn as soon as the rounded portion 87 bears against its point 59. Under the 55 action of this movement, the lever 61 is pushed back towards the left and the screw stop 63 carried by said lever beyond the pivoting point 14, pushes the push rod 62 with a force which is multiplied by the ratio of the lever arms, that 60 is to say, about ten times the force exerted by the tappet 55 on the lever 61. The push rod 62 bears against the stud 32 and holds it stationary in its slide, at the same time holding stationary the collar 27 on which the point 50 is mounted. 65 By this means the work in which the needle 9

then rises cannot be raised by said needle since the point 50 continues to be firmly pressed against said work.

At the same time, as soon as the collar 121 rises, the nose 8 of the pawl 70 is no longer held by the stop 58 and the pawl can turn in a counter-clockwise direction under the action of the spring 71. The tooth of the pawl then engages with the toothed sector 65 in the position occupied by the latter. The collar 121 continuing to rise, and 10 with it, the member 4 which it carries, the heel 72 of the pawl support 66 soon bears against the slope 73 of the member 4, then against the succeeding vertical portion and is thereby drawn back towards the right by means of the spring 67. 15 It of course carries with it in this movement the pawl 70 which it supports and said pawl consequently engages with a certain tooth of the sector 65, according to the position occupied by the latter. During this movement the lug 84 is raised 20 with the collar 121 to which it is secured, said lug having begun to slip on the blade 78 without moving the latter with it, owing to the fact that said blade is, on the other hand, firmly pressed by the spring 82 against the lug 83. However, 25 when the lug 84 has come to bear against the stop 79, it raises with it the blade 78. The roller 81 which is fixed on said blade rises, first of all in the vertical portion of the groove 75 then in the oblique portion of the latter. As the roller 81 is 30 secured to the blade 78 which can only move longitudinally, the roller 81 which is then in the oblique portion of the groove 75, rocks the lever 73 in which said groove is provided, causing it to swing about its axis 77 in a counterclockwise direction. 35

As already stated, the pin 85 is fixed on the lever 76. The pivoting of the lever 76 causes the pin 85 to rotate about 77 in a counterclockwise direction, and it carries with it the lever 53 40 which in its turn pivots about the axis 54, and which will consequently pivot in a clockwise direction: the point 50 which is pressed against the work will consequently move forward towards the needle, carrying with it the work then 45 rising up from the latter, owing to the fact that it describes a circle with the point 54 as centre and consequently tends to move away from the work which is approximately the tangent to said circle perpendicular to the vertical radius passing through 54. This movement, moreover, only 50 takes place at the end of the time which the lug 84 takes to come into contact with the stop 79, which time corresponds to that which the needle 55 takes to leave the work. 55

It will be noted in this connection that the position of the pin 85 can be modified on the lever 76. This enables the travel of the point 50 to be lengthened or shortened, by altering the distance of the pin 85 from the two pivot points 54 and 77 of the levers 53 and 76. 60

When the collar 121 reaches a position near the upper end of its travel, the rounded portion 81 has passed the point 59 of the tappet, and the flat face 11 of the tappet bears against the face 57 of the collar, then at the end of the travel the point 59 turns beneath the stop 58. At this moment the point which is at the end of the lever 61 is no longer pushed by the projecting 70 face 60 of the tappet, and the lever 61 is finally 75 unlocked so as to be in this position when the collar 121 reaches its top dead centre.

At the beginning of the down stroke, the lug 84 of the collar 121 moves away from the stop 79, 75

and does not carry with it the blade 78 for the same reason as previously, since the latter is braked by the spring 82. It only carries said blade with it when it has encountered the stop 80, but during this time, the needle 9 has moved down on the work and holds the latter. During this time, the stop 58 of the left end of the collar 121 has encountered the point 59 of the tappet, so that the locking lever 61 is released and the push stud 62 ceases to act on the rod 32. This is the case for the whole duration of the down stroke.

When the lower portion of the lug 84 encounters the stop 80 of the blade 78, the latter moves downward, and, with it the roller 81 which it carries, which moves down in the slot 75. By this means the lever 76 returns to its vertical position rotating about 77 in a clockwise direction and this causes, in a converse manner to that which was followed during the raising, of the collar 121, the lever 53 to rotate, and with it the point 50 which returns to its original position towards the right. Immediately before this return movement, the heel 72 of the pawl holder 66 is pushed by the inclined portion 73 of the member 4. The pawl holder 66 then rocks about the pin 64 in a counterclockwise direction carrying with it the pawl 70 which is in engagement in the toothed sector 65. This toothed sector 30 then likewise rotates in the same direction about the pin 64 and, through the instrumentality of the pin 68 which passes in the slot 69 of the lever 5, raises the stud 32 and with it, the collar 27, the lever 53 and the point 50 which are carried by said collar. The point 50 has therefore been brought backwards and raised by two different mechanisms.

At the end of the stroke, the stop 58 bears on the tail 8 of the pawl 70 which is raised and releases the sector 65. As the latter is no longer held, the collar 27 falls down, bringing back the sector 65 into its starting position and the point 50 bears against the work. At the same time, the point 59 of the tappet 55 has been passed by the flat portion 57 of the collar 121 and has placed itself in the rounded portion 87 under the action of the spring 56.

In short, the following operations take place:

A. Raising of the needle with the loop of thread. The needle holder, through the instrumentality of the clamping ring carries with it the cast-off as the needle comes out of the work, by means of a known mechanism. During this time the point forming the presser foot is locked.

B. The work moves forward under the action of the presser-foot.

C. The presser foot is unlocked, the needle and the cast-off move downwards.

D. Raising of the presser foot and backward movement of same while the needle penetrates into the work, the cast-off stopping on the work.

E. The presser foot comes down again on the work and the thread is looped on the hook of the needle.

It will be seen from the above sequence of operations that the point 50 which forms the presser-foot and at the same time feeds the work forward, is brought to bear against the work under the action of its weight and that of the parts which carry it, said movement being aided by the action of the spring 134 which acts on the collar 27; it is therefore always automatically at the exact height which corresponds to the thickness of the work, the point raising mechanism 75 constituted by the pawl 70 and the toothed sector

65 always operating in the same manner whatever may be the height at which said point is stopped.

We claim:

1. A portable shoe stitching machine, comprising in combination, a frame member, a head mounted on said frame member, a table mounted on the base of said frame member, a shoe-supporting member secured to said table, a thread looper mounted within said shoe-supporting member, a needle-holder mounted in the head 10 of the machine and operatively connected to a member adapted to slide in said head, said looper and said sliding member being driven simultaneously, the former through a gear train, the latter through a connecting rod, means for feeding forward the work, cam means associated with said sliding member and adapted to actuate said work feeding means at the end of the ascending stroke of the needle-holder, a fixed bearing on said head for supporting said needle-holder, a collar displaceable vertically relatively to said bearing, work clamping means secured to said collar, resilient means for normally holding said collar in engagement with said bearing, means associated with said bearing for limiting and guiding the 25 displacements of said collar relatively to said bearing, and means for holding said collar stationary during the stroke of the needle-holder, to prevent the displacement of said work clamping means relatively to the work, and for releasing 30 said collar when the needle holder is at the end of its upstroke.

2. A portable shoe stitching machine, comprising in combination, a frame member, a head mounted on said frame member, a table mounted 35 on the base of said frame member, a shoe-supporting member secured to said table, a thread looper mounted within said shoe-supporting member, a needle-holder mounted in the head of the machine and operatively connected to a 40 member adapted to slide in said head, a sleeve surrounding said needle-holder and adapted to slide thereon, stops on said sleeve disposed to cooperate with said needle holder, said looper and said sliding member being driven simultaneously, 45 the former through a gear train, the latter through a connecting rod, means for feeding forward the work, cam means associated with said sliding member and adapted to actuate said work feeding means at the end of the ascending stroke 50 of the needle holder, a fixed bearing on said head for supporting said needle-holder, a collar displaceable vertically relatively to said bearing, work clamping means secured to said collar, resilient means for normally holding said collar in 55 engagement with said bearing, means associated with said bearing for limiting and guiding the displacements of said collar relatively to said bearing, means for holding said collar stationary during the stroke of the needle-holder to prevent 60 the displacement of said work clamping means relatively to the work, and for releasing said collar when the needle-holder is at the end of its upstroke, and means associated with the frame of the machine for braking the movement of said 65 needle-holder so as to prevent the displacement thereof save when such displacement is positively effected by the stops of said sleeve.

3. A portable shoe stitching machine, comprising in combination, a frame member, a head 70 mounted on said frame member, a table mounted on the base of said frame member, a shoe-supporting member secured to said table, a thread looper mounted within said shoe-supporting member, a needle-holder mounted in the head 75

of the machine and operatively connected to a member adapted to slide in said head, a needle mounted in said needle-holder, said looper and said sliding member being driven simultaneously by means of a crank handle driving the looper through a gear train, and at the same time rotating a toothed wheel on which is mounted a connecting rod for reciprocating said sliding member, a sleeve surrounding said needle-holder and adapted to slide thereon, stops on said sleeve disposed to cooperate with said needle-holder, a fixed bearing in said head for supporting said needle-holder, a collar displaceable vertically relatively to said bearing, a combined work clamping and feeding means pivotally mounted on said collar and adapted to feed the work forward at the required instant, cam means associated with said sliding member and adapted to actuate said combined work clamping and feeding means at the end of the ascending stroke of the needle-holder, resilient means normally holding said collar in engagement with said bearing, means associated with said bearing for limiting and guiding the displacements of said collar relatively to said bearing, means for holding said collar stationary during the stroke of the needle-holder to prevent the displacement of the work clamping and feeding means relatively to the work, and for releasing said collar when the needle-holder is at the end of its upstroke, a ring secured to said needle-holder, and a cast-off slidably mounted in said ring and cooperating with said needle, said cast-off sliding in said ring when the latter has descended into contact with the work, and being brought back to its position of rest by a spring when the needle-holder rises again.

4. A portable shoe stitching machine, comprising in combination, a frame member, a head mounted on said frame member, a table mounted on the base of said frame member, a shoe-supporting member secured to said table, a thread looper mounted within said shoe-supporting member, a needle-holder mounted in the head of the machine and operatively connected to a member adapted to slide in said head, a needle mounted in said needle-holder, said looper and said sliding member being driven simultaneously by means of a crank handle driving the looper through a gear train and at the same time rotating a toothed wheel on which is mounted a connecting rod for reciprocating said sliding member, a sleeve surrounding said needle-holder and adapted to slide thereon, stops on said sleeve disposed to cooperate with said needle-holder, a fixed bearing in said head for supporting said needle-holder, a collar displaceable vertically relatively to said bearing, a combined work clamping and feeding means pivotally mounted on said collar and adapted to feed the work forward at the required instant, cam means associated with said sliding member and adapted to actuate said combined work clamping and feeding means at the end of the ascending stroke of the needle-holder, resilient means normally holding said collar in engagement with said bearing, means associated with said bearing for limiting and guiding the displacements of said collar relatively to said bearing, means for holding said collar stationary during the stroke of the needle-holder to prevent the displacement of the combined presser foot and work feeding member relatively to the work, and for releasing said collar when the needle-holder is at the end of its upstroke, a ring secured to said needle-holder, a cast-off slidably mounted in said ring and cooperating with said needle, said cast-off sliding in said ring when the latter has descended into contact with the work, and being brought back to its position of rest by a spring when the needle-holder rises again, means cooperating with said sliding member for automatically raising said collar and combined presser foot and work feeding member at the required instant, and means for locking said collar to prevent said combined presser foot and work feeding member from rising while the needle is coming out of the work.

6. A portable shoe stitching machine, comprising in combination, a frame member, a head mounted on said frame member, a table mounted on the base of said frame member, a shoe supporting member secured to said table, a thread looper mounted within said shoe-supporting member, a needle-holder mounted in the head of the machine and operatively connected to a member adapted to slide in said head, a needle mounted in said needle-holder, said looper and said sliding member being driven simultaneously by means of a crank handle driving the looper through a gear train and at the same time rotating a toothed wheel on which is mounted a connecting rod for reciprocating said sliding member, a sleeve surrounding said needle-holder and adapted to slide thereon, stops on said sleeve disposed to cooperate

needle, said cast-off sliding in said ring when the latter has descended into contact with the work, and being brought back to its position of rest by a spring when the needle-holder rises again, and means cooperating with said sliding member for automatically raising said collar and combined work clamping and feeding means at the required instant.

5. A portable shoe stitching machine, comprising in combination, a frame member, a head mounted on said frame member, a table mounted on the base of said frame member, a shoe-supporting member secured to said table, a thread looper mounted within said shoe-supporting member, a needle-holder mounted in the head of the machine and operatively connected to a member adapted to slide in said head, a needle mounted in said needle-holder, said looper and said sliding member being driven simultaneously by means of a crank handle driving the looper through a gear train and at the same time rotating a toothed wheel on which is mounted a connecting rod for reciprocating said sliding member, a sleeve surrounding said needle-holder and adapted to slide thereon, stops on said sleeve disposed to cooperate with said needle-holder, a fixed bearing on said head for supporting said needle-holder, a collar displaceable vertically relatively to said bearing, a combined presser foot and work feeding member pivotally mounted on said collar, and adapted to feed the work forward at the required instant, cam means associated with said sliding member and adapted to actuate said combined presser foot and work feeding member at the end of the ascending stroke of the needle, resilient means normally holding said collar in engagement with said bearing, means associated with said bearing for limiting and guiding the displacements of said collar relatively to said bearing, means for holding said collar stationary during the stroke of the needle-holder to prevent the displacement of the combined presser foot and work feeding member relatively to the work, and for releasing said collar when the needle-holder is at the end of its upstroke, a ring secured to said needle-holder, a cast-off slidably mounted in said ring and cooperating with said needle, said cast-off sliding in said ring when the latter has descended into contact with the work, and being brought back to its position of rest by a spring when the needle-holder rises again, means cooperating with said sliding member for automatically raising said collar and combined presser foot and work feeding member at the required instant, and means for locking said collar to prevent said combined presser foot and work feeding member from rising while the needle is coming out of the work.

6. A portable shoe stitching machine, comprising in combination, a frame member, a head mounted on said frame member, a table mounted on the base of said frame member, a shoe supporting member secured to said table, a thread looper mounted within said shoe-supporting member, a needle-holder mounted in the head of the machine and operatively connected to a member adapted to slide in said head, a needle mounted in said needle-holder, said looper and said sliding member being driven simultaneously by means of a crank handle driving the looper through a gear train and at the same time rotating a toothed wheel on which is mounted a connecting rod for reciprocating said sliding member, a sleeve surrounding said needle-holder and adapted to slide thereon, stops on said sleeve disposed to cooperate

- with said needle-holder, a fixed bearing in said head for supporting said needle-holder, a collar displaceable vertically relatively to said bearing, a combined presser foot and work feeding means 5 pivotally mounted on said collar, and adapted to feed the work forward at the required instant, cam means associated with said sliding member and adapted to actuate said combined presser foot and work feeding member at the end of the 10 ascending stroke of the needle, resilient means normally holding said collar in engagement with said bearing, means associated with said bearing for limiting and guiding the displacements of said collar relatively to said bearing, means for 15 holding said collar stationary during the stroke of the needle-holder to prevent the displacement of the combined presser foot and work feeding member relatively to the work, and for releasing said collar when the needle-holder is at the end 20 of its upstroke, a ring secured to said needle-holder, a cast-off slidably mounted in said ring and cooperating with said needle, said cast-off sliding in said ring when the latter has descended into contact with the work, and being brought 25 back to its position of rest by a spring when the needle-holder rises again, means cooperating with said sliding member for automatically raising said collar and combined presser foot and work feeding member at the required instant, and a push 30 rod slidably mounted in said bearing and cooperating with one end of a two-armed lever, the other end of which is pushed by a cam mounted on the head thereby preventing said combined presser foot and work feeding member from rising 35 while the needle is coming out of the work.
7. A portable shoe stitching machine, comprising in combination, a frame member, a head mounted on said frame member, a table mounted on the base of said frame member, a shoe-supporting member secured to said table, a thread looper mounted within said shoe-supporting member, a needle-holder mounted in the head of the machine and operatively connected to a member adapted to slide in said head, a needle mounted 40 in said needle-holder, said looper and said sliding member being driven simultaneously by means 45 of a crank handle driving the looper through a gear train and at the same time rotating a toothed wheel on which is mounted a connecting rod for reciprocating said sliding member, a sleeve surrounding said needle-holder and adapted to slide thereon, stops on said sleeve disposed to cooperate with said needle-holder, a fixed bearing in said head for supporting said needle holder, a collar displaceable vertically relatively to said bearing, a combined presser foot and work feeding means pivotally mounted on said collar, and adapted to feed the work forward at the required instant, cam means associated with said sliding member and adapted to actuate said combined presser foot and work feeding member at the end of the ascending stroke of the needle, resilient means normally holding said collar in engagement with said bearing, means associated with said bearing for limiting and guiding the displacements of said collar relatively to said bearing, means for holding said collar stationary during the stroke of the needle-holder to prevent the displacement of the combined presser foot and work feeding member relatively to the work, and for releasing said collar when the needle-holder is at the end of its upstroke, a ring secured to said needle-holder, a cast-off slidably mounted in said ring and cooperating with said needle, said cast-off sliding in said ring when the latter has descended into contact with the work, and being brought back to its position of rest by a spring when the needle-holder rises again, means cooperating with said sliding member for automatically raising said collar and combined presser foot and work feeding means at the required instant, a push rod slidably mounted in said bearing and cooperating with one end of a two-armed lever, the other end of which is pushed by a cam mounted on the head thereby preventing said combined presser foot and work feeding member from rising while the needle is coming out of the work, and means for rocking said combined presser foot and work feeding member without preventing the vertical displacement of the latter.

ARTHUR LOUIS FIQUET.
